UNITED STATES PATENT OFFICE

97,851

DESIGN FOR A CABINET FOR A REFRIGERATOR

Albert Kahn, Detroit, Mich.

Application October 3, 1935, Serial No. 58,825

Term of patent 3½ years

To all whom it may concern:

Be it known that I, Albert Kahn, a citizen of the United States, residing at Detroit, in the county of Wayne and State of Michigan, have invented a new, original, and ornamental Design for a Cabinet for a Refrigerator, of which the following is a specification, reference being had to the accompanying drawing, forming part thereof.

I claim:

The ornamental design for a cabinet for a refrigerator, as shown.

ALBERT KAHN.
